UNITED STATES PATENT OFFICE.

WILLIAM S. HALSEY, OF PITTSBURG, PENNSYLVANIA.

MEANS FOR TRANSMITTING FLUID UNDER PRESSURE.

SPECIFICATION forming part of Letters Patent No. 718,250, dated January 13, 1903.

Application filed June 19, 1902. Serial No. 112,293. (No model.)

To all whom it may concern:

Be it known that I, WILLIAM S. HALSEY, of Pittsburgh, in the county of Allegheny and State of Pennsylvania, have invented a certain new and useful Improvement in Means for Transmitting Fluid under Pressure, of which improvement the following is a specification.

My present invention relates to and is an improvement in apparatus for transmitting fluid under pressure from a supply-reservoir to a device or mechanism in which it is to be utilized of the general class or type in which a receiver is fitted to traverse longitudinally on a fixed feed pipe or reservoir and to communicate therewith in its traverse through ports or openings controlled by automatically-operated valves for the admission of fluid under pressure from the reservoir to the receiver, such fluid being conducted through suitable tubular connections from the receiver to the desired point of supply. Instances of apparatus of the class referred to are exemplified in Letters Patent of the United States No. 532,198, granted and issued to me under date of January 8, 1895; Nos. 637,333 and 653,802, granted to the Pneumatic Crane Company, as my assignee, under dates of November 21, 1899, and July 17, 1900, respectively, and No. 693,516, granted to me under date of February 18, 1902.

The chief object of my invention is to provide means whereby the receiver may be caused to conform to the conditions of curvature of the reservoir or air-line feed-pipe while passing along it, and thereby to prevent the undue amount of friction and the tendency to closure of the supply-valves which are occasioned by the traverse of a straight rigid receiver on a reservoir, which is by such traverse of the receiver diverted from its normal straight longitudinal line and forced successively into short bends adjacent to the ends of the portions of its length which the receiver successively incloses as it passes along it.

A further object of my invention is to provide an improved supply-valve mechanism by the employment of which a free supply of fluid may be insured, friction and wire drawing effectually prevented, and the valve-operating tappets adapted to operate with reduced

lift and without tendency to being bent when contacted with by the receiver.

The improvement claimed is hereinafter fully set forth.

In the accompanying drawings, Figure 1 is a vertical longitudinal central section through a portion of a fluid-pressure-transmission apparatus, illustrating an application of my invention; Fig. 2, a similar section through one end of the inner or guide casing of the receiver; Figs. 3 and 3^a, transverse sections at the lines *x x* and *y y*, respectively, of Fig. 1; Fig. 4, a vertical longitudinal central section, on an enlarged scale, through one of the valve-casings of the reservoir; Fig. 5, a view, partly in elevation and partly in section, of a valve-actuating tappet and its shoe; Fig. 6, a transverse section through the valve-casing in the axial plane of a supply-valve; Fig. 7, a vertical longitudinal central section through the guide-casing of the receiver; Fig. 8, a view in elevation and on a reduced scale of a receiver which is rigid and preliminarily bent to a curvature according with that assumed by a reservoir; Fig. 9, a similar view of a receiver composed of a plurality of articulated sections; Fig. 10, an end view, on an enlarged scale, of a section of the same; Fig. 11, a side view in elevation of a section of the same, and Fig. 12 a transverse section through a reservoir having a longitudinal tappet-ledge and guide-strips.

My invention is herein, as in the several Letters Patent above mentioned, shown as applied in connection with a reservoir or air-line feed-pipe 1 for the reception of fluid under pressure, which extends throughout the length over which the apparatus is desired to operate, and a receiver 2, which surrounds a portion of the length of and is movable longitudinally on the reservoir and is provided with packing 3 near its ends, forming fluid-tight joints with the reservoir, and with tapered or inclined end faces 4 for actuating the supply-valves 5 thereof. The valves 5 control supply ports or openings 5^a in cast-metal valve-casings which form portions of the length of the reservoir, the intermediate portions being formed of comparatively light tubes. The supply-ports when uncovered establish communication between the reservoir and the receiver, and they are located at

such distances apart in the length of the reservoir that one or more of them will always be within the receiver. The reservoir is suitably supported at proper intervals, and the 5 receiver is supported upon a track or runway (not shown) by brackets having wheels or rollers which traverse on the runway. The supporting devices being familiar to those skilled in the art and not forming part of my 10 present invention are not herein illustrated or described.

In the general features above stated the construction herein set forth accords substantially with those of the Letters Patent 15 before referred to, and said general features are not in and of themselves claimed as of my present invention.

The supply-valves 5 are fitted to traverse on guide-stems 5^b, fixed in removable bushings 5^c, which are secured in the valve-casings of the reservoir 1, the inner faces of the bushings forming seats for the valves and the supply-ports 5^a extending through the bushings. Each of the valves 5 controls two 20 oppositely-located supply-ports 5^a, and in order to prevent the undue friction between the receiver and the reservoir by the reaction of the escaping air the supply-ports are balanced by being formed in or nearly in the 25 same axial line, so that the resultant reaction of the escape of air from one of each pair of ports will be counterbalanced by that of the other and there will be no tendency to force the receiver against the reservoir. The valves 30 5 are disposed in pairs, and the two valves of each pair are actuated by a single intermediate tappet 6, which acts upon them through a tappet-lever 7, to the ends of which the valves are coupled by pins 7^b. In the 35 constructions of the Letters Patent before referred to each of the supply-valves was actuated by a pair of tappets, and the tappets were raised to unseat the valves by contact with a rigid longitudinal rib, bearing-face, or 40 45 tappet-ledge fixed to the inner surface of the shell or wall of the receiver and abutting against the outer surface of the reservoir.

Under my present invention the straight rigid tappet-ledge theretofore employed is 50 dispensed with, and the longitudinal member of the receiver, which actuates the tappets, is maintained in contact with the periphery of the reservoir, either by being made of sufficient elasticity to conform to the curvature 55 which is assumed by the reservoir or by being permanently bent into a corresponding curve. In the former case the receiver is preferably provided with an inner or guide casing 8, which may be, as shown, formed of 60 tubing sufficiently light to be flexible, and which is secured at its ends to the heads of the receiver and fits intermediately freely around the reservoir 1. The flexibility of the casing 8 may, if desired, be increased by making saw-cuts 8^b partially around it at suitable distances apart in its length, as shown in Fig. 7, and at points adjacent to its ends

it is bent to form inclines 8^c, by contact with which the tappets 6 are raised to unseat the supply-valves 5. Two rows of perforations 8^a, corresponding substantially in diameter with the supply-ports 5^a, are formed in the casing 8 throughout its length, through which perforations the fluid under pressure which is released from the reservoir by the unseating of the supply-valves passes into the receiver, and is thence led to the mechanism or appliance in which it is to be utilized through a supply-passage 16, to which a supply-pipe leading to said mechanism or appliance may 80 be connected.

As before stated, the two valves of each pair are actuated by a single intermediate tappet 6. Each of the tappets 6 is provided with a T-head 6^a, which fits in a longitudinal recess in a tappet-lever 7, to each end of which a supply-valve 5 is coupled by a pin 7^b. The tappets are fitted to slide freely in guide-bushings 6^b, fixed in the valve-casings of the reservoir, and their lower ends are provided 90 with shoes 6^c of larger diameter, which abut against the adjacent surfaces of the guide-casings 8 and traverse with the tappets in sockets formed in the bushings 6^b. An opening 6^d formed in the shoe 6^c enables the shoe 95 to be forced off the tappet when required.

The supply-valves 5 are normally closed and held seated, as shown in Fig. 4, by the fluid-pressure in the reservoir and by their gravity and that of the connected tappet-levers 7. When in the longitudinal movement of the receiver 2 its forward or leading inclined face 4 abuts against the shoe 6^c of one of the tappets 6, it raises said tappet to the inner limit of its traverse, thereby permitting the further traverse of the receiver to be effected. The elevation of the tappet causes its T-head 6^a to act on the tappet-lever 7 and to move said lever about the pin 7^b, by which it is connected to the valve 5 farther from the leading end of the receiver as a fulcrum, said valve, which is not at this time within the receiver, being held seated by the preponderance of reservoir-pressure on its top above the atmospheric pressure below it. The valve connected to the opposite end of the tappet-lever is unseated by the movement thereof, and this valve being within the receiver delivers air thereto from the reservoir through the supply-ports 5^a, which it 110 controls. When the leading end of the receiver has passed the unseated valve, the tappet drops down a reverse incline to a short horizontal portion of the guide-casing 8 between its leading end and the adjacent incline 115 8^c, and both valves will be seated during its traverse over said horizontal portion. When the leading incline 8^c strikes the tappet-shoe 6^c, the tappet will be raised as before; but as both valves are now within the receiver and 120 both are exposed to the same preponderance of downward pressure there will be no greater resistance to the unseating of one valve of the pair than to that of the other. The tappet-

lever will therefore be raised equally at both ends by the movement of the tappet and both valves of the pair will be simultaneously unseated. The valves will remain unseated for 5 the delivery of fluid from the reservoir to the receiver until the incline 8° at the rear or following end of the receiver passes under the tappet-shoe, when both valves will be seated, thereafter the valve within the receiver be 10 unseated, and finally both valves be seated correspondingly with their successive operation at the leading end of the receiver, as before described.

It will be obvious to those skilled in the art 15 that the essential and characteristic feature of my invention consists in a receiver provided with a longitudinal bearing or tappet-ledge which is adapted to conform to the curvature assumed by the reservoir, where the 20 reservoir is surrounded by the receiver, either by possessing a sufficient degree of flexibility to follow and conform to the curvature of the reservoir without yielding sufficiently to permit total or partial closure of the supply- 25 valves during such periods as they should be and remain unseated or by being preliminarily and permanently bent to the same curvature. My present invention is not, therefore, limited to the specific form and construction 30 of receiver and longitudinal bearing member herein shown and within the conditions above stated. The same may be varied in the discretion of the skilled mechanic without departure from the spirit and operative principle 35 of my invention. Thus, for example, the receiver may, as before stated, be made rigid and preliminarily bent to approximately the same curvature as that which will be assumed by the suspended reservoir or air line, as 40 shown in Fig. 8, or may be made up of a plurality of articulated sections, as shown in Figs. 9, 10, and 11. In this case the several sections 2 of the receiver are connected by flexible steel rods 2^a, passing through lugs 2^b on the sections. Again, instead of making the case in the form of a tube entirely 45 surrounding the reservoir and provided with longitudinal rows of perforations, as hereinbefore set forth, a longitudinal bearing or 50 tappet-ledge 8^d and two or more longitudinal guide-strips 8^e, disposed at proper intervals around and abutting on the periphery of the reservoir and connected to the receiver, as 55 shown in Fig. 12, may be employed, such structural modification being the mechanical equivalent of and performing the same functions as the specific construction of guide-tube herein shown and described.

I claim as my invention and desire to secure by Letters Patent—

1. The combination of a fluid-pressure reservoir, a receiver surrounding and movable longitudinally thereon, a supply-valve seated over a port in the reservoir, a tappet extending through the shell of the reservoir and adapted to unseat the supply-valve, and a longitudinal member fixed to the receiver and

adapted to abut against the tappet and conform to the curvature assumed by the portion of the reservoir which is surrounded by 70 the receiver.

2. The combination of a fluid-pressure reservoir, a receiver surrounding and movable longitudinally thereon, a supply-valve seated over a port in the reservoir, a tappet extending through the shell of the reservoir and adapted to unseat the supply-valve, and a longitudinal member fixed to the receiver and having flexibility whereby it is adapted to abut against the tappet and conform to the 80 curvature assumed by the portion of the reservoir which is surrounded by the receiver.

3. The combination of a fluid-pressure reservoir, a receiver surrounding and movable longitudinally thereon, a supply-valve seated over a port in the reservoir, a tappet extending through the shell of the reservoir and adapted to unseat the supply-valve, and a longitudinal member fixed to the receiver and adapted to abut against the tappet and conform to the 90 curvature assumed by the portion of the reservoir which is surrounded by the receiver, and being outwardly inclined from the reservoir adjacent to each of its ends.

4. The combination of a fluid-pressure reservoir, a receiver surrounding and movable longitudinally thereon, a supply-valve seated over a port in the reservoir, a tappet extending through the shell of the reservoir and adapted to unseat the supply-valve, and a flexible member fixed to the receiver and abutting longitudinally on the reservoir in line with the tappet and also on two or more lines at other portions of the periphery of the reservoir.

5. The combination of a fluid-pressure reservoir, a receiver surrounding and movable longitudinally thereon, a supply-valve seated over a port in the reservoir, a tappet extending through the shell of the reservoir and adapted to unseat the supply-valve, and a flexible member fixed to the receiver and abutting longitudinally on the reservoir in line with the tappet and also on two or more lines at other portions of the periphery of the reservoir, said flexible member being outwardly inclined from the reservoir adjacent to each of its ends in a longitudinal plane intersecting the tappet.

6. The combination of a fluid-pressure reservoir, a receiver surrounding and movable longitudinally thereon, a supply-valve seated over a port in the reservoir, a tappet extending through the shell of the reservoir and adapted to unseat the supply-valve, and a flexible inner or guide tube fixed to the receiver and surrounding the reservoir, said tube being outwardly inclined from the reservoir adjacent to each of its ends in a longitudinal plane intersecting the tappet and being provided with a plurality of perforations adapted to communicate with the port of the supply-valve.

7. The combination of a fluid-pressure res-

- ervoir, a receiver surrounding and movable longitudinally thereon, a pair of supply-valves, each seated over a port in the reservoir, a tappet extending through the shell of the reservoir intermediate of the supply-valves of the pair, means for unseating said supply-valves by movement of the tappet, and a bearing-surface fixed to the receiver in position to contact with the tappet.
- 10 8. The combination of a fluid-pressure reservoir, a receiver surrounding and movable longitudinally thereon, a pair of supply-valves, each seated over a port in the reservoir, a tappet extending through the shell of the reservoir intermediate of the supply-valves of the pair, a tappet-lever coupled, at its ends, to said valves and resting on the tappet, and a bearing-surface fixed to the receiver in position to contact with the tappet.
- 15 9. The combination of a fluid-pressure reservoir, a receiver surrounding and movable longitudinally thereon, a pair of supply-valves, each seated over a port in the reservoir, a tappet extending through the shell of the reservoir intermediate of the supply-valves of the pair and having a T-head within the reservoir, a tappet-lever coupled, at its ends, to said valves and resting on the

T-head, and a bearing-surface fixed to the receiver in position to contact with the tappet. 30

10. The combination of a fluid-pressure reservoir, a receiver surrounding and movable longitudinally thereon, a supply-valve seated over a port in the reservoir, a tappet extending through the shell of the reservoir, a shoe of larger diameter fitting over the outer end of the tappet, means for unseating the supply-valve by movement of the tappet, and a bearing-surface fixed to the receiver in position to contact with the tappet. 35

11. The combination of a fluid-pressure reservoir, a receiver surrounding and movable longitudinally thereon, a pair of oppositely-located supply-ports, passing through the shell of the reservoir and having their axes substantially in line to eliminate friction due to reaction, a supply-valve controlling both supply-ports, a tappet extending through the shell of the reservoir, means for unseating the supply-valve by movement of the tappet, 40 and a bearing-surface fixed to the receiver in position to contact with the tappet. 50
